UNITED STATES PATENT OFFICE.

WILLIAM F. BAAR, OF GRAND RAPIDS, MICHIGAN.

CUTTER HEAD.

Application filed January 19, 1925. Serial No. 3,338.

This invention relates to improvements in cutter heads for wood working machinery, especially for jointers, shapers and the like and its object is to provide a cutter head 5 made from a single piece of metal whereby the cutting edges are always maintained in proper alignment and the article may be made very cheaply.

The structure of this invention lends it 10 self particularly well to the manufacture of cutter heads having the blades arranged alternately at different angles relative to the axis of rotation for the purpose of working on woods having crossed and knurly 15 grains.

The invention is hereafter more fully described and particularly pointed out in the claim reference being had to the accompanying drawings in which,

20 Fig. 1 is an end view of a cutter head made in accordance with the invention.

Fig. 2 is a vertical transverse section on the line 2—2 of Fig. 1.

25 Fig. 3 is a horizontal transverse section on the line 3—3 of Fig. 1 and

Fig. 4 is a perspective view of the device.

Like numbers refer to like parts in all of the figures.

The device comprises the substantially 30 disk-shaped body portion 1 having a central aperture 2 adapting it to fit upon the spindle of the machine in which it is used, the body being clamped by a nut against a shoulder as is ordinary practice with such devices. Formed integrally with the body are the diametrically opposite forwardly turned flanges 3 and also the diametrically opposite rearwardly turned flanges 4, the flanges 3 being arranged ninety degrees 35 around the body from the flanges 4.

The blades 5 each having a cutting edge 6 are also formed integrally with the body

portion and with the flanges 3 and 5, the forward edges of the blades merging into the flanges 3 and the rearward edges of the 45 blades merging into the flanges 4.

The cutter shown in the drawing is of the type in which the alternate blades are oppositely inclined relative to the axis of rotation of the cutter and the structure embodying 50 this invention is particularly well adapted to the formation of the blades so arranged.

The whole device is forged from a relatively flat piece of steel which may be easily cut and worked. Although it is possible to 55 form these cutter heads singly by hand forging it is advisable to provide dies for their manufacture and after the proper dies have been made the cutter heads may be manufactured by their use very economical- 60 ly, much more cheaply than the customary built up style of cutter head, and they are just as efficient in operation and more desir- 65 able than the old style because the blades always have their proper alignment and radial adjustment and there is no chance of the blades becoming loose and flying out while in operation.

I claim:

A cutter head formed from a single piece 70 of relatively thin metal comprising a disk-like body portion having a central aperture and arranged in the plane of rotation, blades formed integrally with the body portion ex- 75 tending radially from the body and ar- ranged in angular relation to the body and to the axis of rotation and flanges formed integrally with the body and the blades and extending forwardly and rearwardly respec- 80 tively from the body and merging into the blades to stiffen them.

In testimony whereof I affix my signature.

WILLIAM F. BAAR.
